US0D1000416S

(12) **United States Design Patent** (10) **Patent No.:** **US D1,000,416 S**
(45) **Date of Patent:** **** Oct. 3, 2023**

(54) **WIRELESS HEADPHONES**

(71) Applicant: **New Audio LLC**, New York, NY (US)

(72) Inventors: **Thomas C. Wilson**, Brooklyn, NY (US); **Clayton J. Pipkin**, Highland Park, NJ (US); **Marten Wallby**, Malmö (SE); **Zachary Hellman**, New York, NY (US); **Jonathan Levine**, New York, NY (US)

(73) Assignee: **New Audio LLC**, New York, NY (US)

(**) Term: **15 Years**

(21) Appl. No.: **29/796,516**

(22) Filed: **Jun. 24, 2021**

(51) LOC (14) Cl. **14-01**

(52) U.S. Cl.

USPC **D14/206**; D14/226

(58) **Field of Classification Search**

USPC D14/206, 205, 226; D29/112; 2/209; 381/380-381, 370, 374, 362, 382; 181/129

CPC H04R 25/00; H04R 25/02; H04R 1/1066; H04R 1/1016; H04R 5/033; H04R 5/0335; H04R 1/1058; H04R 1/08; H04R 11/06; H04R 19/04; H04R 1/1091; H04R 11/04; H04R 1/1008; H04R 1/105

(57) **CLAIM**

The ornamental design for wireless headphones, as shown and described.

DESCRIPTION

FIG. 1 is a perspective view of wireless headphones showing our first new design, viewed from the top and front.

FIG. 2 is a top plan view thereof.

FIG. 3 is a bottom plan view thereof.

FIG. 4 is a front profile view thereof.

FIG. 5 is a back profile view thereof.

FIG. 6 is a first side profile view thereof; and,

FIG. 7 is a second side profile view thereof.

1 Claim, 7 Drawing Sheets
